J. SULLIVAN & W. ROSENSTOCK.
MEASURING APPARATUS.
APPLICATION FILED APR. 13, 1910.

970,765.

Patented Sept. 20, 1910.

UNITED STATES PATENT OFFICE.

JOHN SULLIVAN AND WILLIAM ROSENSTOCK, OF THE UNITED STATES NAVY.

MEASURING APPARATUS.

970,765.

Specification of Letters Patent. Patented Sept. 20, 1910.

Application filed April 13, 1910. Serial No. 555,125.

To all whom it may concern:

Be it known that we, JOHN SULLIVAN and WILLIAM ROSENSTOCK, of the United States Navy, citizens of the United States, have invented new and useful Improvements in Measuring Apparatus, of which the following is a specification.

The object of our invention is to provide an apparatus for measuring liquids, *i. e.*, for drawing off predetermined quantities of liquid from a source of supply, which shall be exceedingly simple of construction and absolutely positive and efficient in operation.

The apparatus characterized by our invention is most admirably adapted for use in saloons, but is, also, susceptible of advantageous use in grocery and other stores, and in wine-cellars of private houses.

By the use of the device of our invention in stores, saloons, and the like, considerable saving of time is effected, and the danger of overflow or withdrawal of more than the desired, predetermined quantity of liquid is obviated.

In drawing a desired predetermined quantity of liquid, in the use of our device, it is simply necessary for the storekeeper, or the like, to place a bottle, can, bucket, or the like, beneath the spigot of our device, and, then, throw a lever, which is accomplished in a mere second of time, and which sets into operation automatically-operating mechanism; he can, then, immediately turn aside and wait upon customers and return to the apparatus to find the bottle, or the like, filled with the desired predetermined quantity of liquid, exit of the liquid having been automatically stopped at the proper time.

With the above objects in view, and others appearing as the specification proceeds, our invention comprehends the novel construction, arrangement, and combination of parts, as fully hereinafter described, set forth in the claims, and illustrated in the accompanying drawing, in which:

Figure 1 is a central, longitudinal section, partly broken away, through our apparatus, certain parts being shown in elevation; and Fig. 2 is a fragmentary, detail view, in front elevation, of the front wall of the casing.

Referring, now, in detail to the drawing: A designates a casing or housing, which may be of any desired shape, in this instance being shown as oblong. Extending preferably through the lower portion of the casing and

longitudinally thereof is a pipe B, communicating, at one end, as at b, with a source of supply of liquid and carrying, at the other end, a spigot b'. Inferiorly of the casing, said pipe carries a valve or faucet b², controlling the passage of liquid through said pipe.

Inferiorly of the casing A and mounted in suitable bearings in the front and rear walls, a², a, respectively, thereof is a revoluble shaft C, preferably disposed toward the upper end of the casing. Carried by said shaft C, toward one end thereof, and movable therewith, is a gear c, and secured to the other end of said shaft, as at c', is one end 70 of a spiral clock-spring c² of considerable strength, the other end whereof is secured to the rear wall a of the casing, as by the pin a'.

The front wall a² of the casing A is provided, toward its upper end, with an arc-shaped slot a³, in which works a pin c', provided at the end thereof which is exterior of the casing with a knob or handle c², and secured at its other end to the gear c. The exterior surface of the front wall a² of the casing is provided, along the slot a³, with graduations and indicia a⁴, such as the numbers and words "½ Pint", "Pint", "Quart", etc. (See Fig. 2.)

Inferiorly of the casing A and disposed beneath and parallel to the shaft C, and mounted in suitable bearings in the front and side walls a², a, of the casing, is another revoluble shaft D, carrying, toward one end, a pinion d, meshing with the gear c. Also 90 carried by said shaft D is a worm d'.

Mounted on the stem of the faucet b² carried by the pipe B is a gear-wheel E, meshing with the worm d'.

It will be seen, by the described construction and combination of the parts, that the farther the pin c' is thrown, the more tightly will the spring c² be wound up and, upon release of the pin, the greater will be the time the spring will take to unwind. Therefore, the operation will be apparent, but, briefly stated, it is as follows. The spigot b' may be always left open, or be normally closed, and the faucet b² is, of course, normally closed, cutting off communication through the pipe B. The relative size of the gear c, the pinion d, the worm d', the gear-wheel E, and the spring c² is so proportioned and adjusted to the degree of velocity of flow of the particular liquid, under gravity or pressure, and

the consequent period of time a given quantity of the particular liquid must consume in passing through the faucet to the outlet spigot b' , that, when the pin c' is thrown 5 from its normal position of inactivity at the end of the slot a^3 to, say, the " $\frac{1}{2}$ Pint" mark or graduation on the slot a^3 , the spring c^2 will be so wound up that it will take a period of time to unwind sufficient to al- 10 low one-half pint of the particular liquid to pass through the faucet b^2 to the exit spigot b' . It will be understood that different liquids are of varying density, and that the velocity of flow thereof is governed partly 15 thereby. Thus, the velocity of flow of molasses, being of considerable density, will be retarded, as compared, say, to that of wine of considerably lesser relative density; and the construction of our devices, under our 20 invention, will, of course, be governed by the kind of liquid in connection with which they will be used. The pin c' is thrown to the desired point, say to the " $\frac{1}{2}$ Pint" mark on the arc-slot a^3 and is, thereupon, immediately 25 released: By the throw, mentioned, of the pin, the gear c will be rotated, the shaft C revolving simultaneously therewith and winding up the spring c^2 ; the pinion d , being in mesh with the gear c , will also be 30 simultaneously rotated, revolving the shaft D and worm d coincidently therewith; the gear-wheel E , being in mesh with the worm d' , will also be synchronously revolved, thus turning the stem of the faucet b^2 and open- 35 ing the same, to allow flow therethrough of the liquid in the pipe B . As said, the pin is immediately released after throwing the same, whereupon the spring c^2 , which has been wound up by said throw of the pin will 40 commence to unwind, thus reversing the prior direction of movement of the different parts and returning them to normal position, thus closing the faucet b^2 and cutting off communication therethrough. It will thus 45 be seen that the faucet b^2 is automatically closed and the flow of liquid from the spigot b' automatically stopped at the desired pre-determined interval of time, requisite to withdraw the desired predetermined quantity 50 of liquid.

It being understood that various slight changes in detail may be made without affecting the spirit of the invention, or sacrificing any of its advantages, and that all 55 such modifications as come within the scope of the appended claims are within the purview of the invention, what we claim and desire to secure by Letters-Patent is:

1. In apparatus for measuring liquids, a 60 pipe adapted to be placed in communication with a source of supply of liquid, and carrying a valve normally closed to cut off communication therethrough, a casing, a revolu- 65 ble shaft supported in bearings in said cas- ing and carrying a gear, a pin secured to

said gear, a clock-spring, one end of which is secured to said shaft and the other end to said casing, a second shaft supported in bearings in said casing and carrying a pinion meshing with said gear and carrying 70 also a worm, and a gear-wheel meshing with said worm and operatively associated with said valve, whereby the throw of the pin winds up said spring and, through said chain of gears, opens said valve and the 75 unwinding of said spring, after release of said pin, returns the parts to normal position and automatically closes said valve.

2. In apparatus for measuring liquids, a 80 casing, a pipe extending therethrough and adapted to be placed in communication with a source of liquid, and carrying a valve normally closed to cut off communication therethrough, a revolute shaft supported in bearings in said casing and carrying a gear, 85 said casing having an arc-shaped slot, a pin working in said slot and secured to said gear, a clock-spring, one end of which is secured to said shaft and the other end to said casing, a second shaft supported in 90 bearings in said casing and carrying a pinion meshing with said gear and carrying also a worm, and a gear-wheel meshing with said worm and operatively associated with said valve, whereby the throw of the pin 95 winds up said spring and, through said chain of gears, opens said valve and the unwinding of said spring, after release of said pin, returns the parts to normal position and automatically closes said valve.

3. In apparatus for measuring liquids, a 100 casing, a pipe extending therethrough and adapted to be placed in communication with a source of supply of liquid, and carrying a valve normally closed to cut off communication therethrough, a revolute shaft supported in bearings in said casing and carrying a gear, said casing having an arc-shaped slot and a scale along said slot, a pin working in said slot and secured to said gear, a 105 clock-spring, one end of which is secured to said shaft and the other end to said casing, a second shaft supported in bearings in said casing and carrying a pinion meshing with said gear and carrying also a worm, 110 and a gear-wheel meshing with said worm and operatively associated with said valve, whereby the throw of the pin winds up said spring and, through said chain of gears, opens said valve and the unwinding of said 115 spring, after release of said pin, returns the parts to normal position and automatically closes said valve.

4. In apparatus for measuring liquids, a 120 pipe adapted to be placed in communication with a source of supply of liquid, and carrying a valve having a stem and normally closed to cut off communication through said pipe, a revolute shaft supported in 125 bearings in said casing and carrying a gear, 130

a pin secured to said gear, a clock-spring, one end of which is secured to said shaft and the other end to said casing, a second shaft supported in bearings in said casing and 5 carrying a pinion meshing with said gear and carrying also a worm, and a gear-wheel meshing with said worm and carried by said valve-stem, whereby the throw of the pin winds up said spring and, through said 10 chain of gears, opens said valve, and the unwinding of said spring, after release of said

pin, returns the parts to normal position and automatically closes said valve.

In testimony whereof we have hereunto set our hands in presence of two subscribers 15
15 witnesses.
